UNITED STATES PATENT OFFICE.

PRESSLEY COLEMAN, OF HAYSVILLE, PENNSYLVANIA.

SWITCH-STAND.

SPECIFICATION forming part of Letters Patent No. 292,897, dated February 5, 1884.

Application filed October 15, 1883. (No model.)

To all whom it may concern:

Be it known that I, PRESSLEY COLEMAN, of Haysville, in the county of Allegheny and State of Pennsylvania, have invented a new and useful Improvement in Switch-Stands; and I do hereby declare the following to be a full, clear, and exact description thereof.

My invention relates to an improvement in safety-lock signal-switches; and it has for its object the setting and locking of the signal mechanism by the switch-lever before the switch can be operated, and the retention of the signal until the switch is brought back to its original position; and it is designed to be used to protect the main line of a railroad at points where a break is caused, as at a siding, junction, or cross-over, where absolute safety-signals are required.

Heretofore in safety-signal switches, where-in the signal devices have been automatically operated from the switch mechanism, the signal has been operated by the first part of the switch movement, and it sometimes happens, and it is always possible, that the switch being unlocked, the lever is turned sufficiently far to partially open the switch without moving the signal sufficiently to denote danger, and also that the lever is moved far enough in the reverse direction to display the safety-signal without moving sufficiently to close the break in the line. These objectionable features are, however, avoided by my invention, which I will now proceed to describe, so that others skilled in the art may manufacture and use the same, reference being had to the accompanying drawings, forming part of this specification, in which—

Figure 1 is an elevation, partly in section, of my improved switch and signal stand. Fig. 2 is a horizontal sectional view through the line $x-x$, Fig. 1. Fig. 3 is a plan view of the operating-disk detached, and Fig. 4 is a side view of the same.

Like letters of reference indicate like parts wherever they occur.

In the drawings, a represents the frame of the stand, extending through the center of which is the vertical switch-rod b , the upper end of which is bolted to a horizontal revolving disk, c , which rests in a suitable way or recess in the top of the frame a .

Extending horizontally from the circumference of the disk c are ears or lugs c' , between which the operating-lever d is pivoted, so that it may be lowered to a vertical position, as shown by the full lines in the drawings, or raised to a horizontal position, as shown by the dotted lines. The lever is so pivoted, however, that it can only be moved on its pivotal point in the line of a vertical plane.

Extending from the end of the lever d beyond the pivotal point is a short arm, e , from which, extending horizontally, is a pin, f , which engages with a half-eye or hook, g , on the end of a horizontal rod or bar, h . This rod h extends over the face of the disk c , being bent so as to pass the signal rod or shaft i .

On the other side of the shaft i , secured to and extending down from the under face of the bar h , is a pin, j , which engages and slides in a groove or way, k , formed in the upper face of the disk c . This groove k extends from the center of the disk in a straight line to a point near the circumference thereof in a line with the direction of the bar h , and thence half-way round the disk, following the line of the circumference. The lower end of the signal-shaft i is mounted loosely in a slot in the center of the disk c , and is further supported by the frame l . The bar h is also supported by passing through slots in this frame.

Keyed to the shaft i , below the bar h , is a collar, m , from which extends a short horizontal arm, n , secured to which and extending upward is a pin, o , which engages in an elliptical slot, p , in the lower face of the bar h . Slots q are formed in the disk v , so as to engage with the lever d , and prevent the disk c from being turned on its axis while the lever is in its vertical position.

Secured to the upper portion of the shaft i are the signal-targets r and a signal-lamp, t .

The lower end of the vertical switch-rod b is connected with the switch-rails in the usual manner.

The operation is as follows: By turning the disk c on its axis, the switch-rod or shaft b is also turned, which operates the switch. In order to turn the disk, however, it is first necessary to raise the lever d to a horizontal position, in order that it may clear the slot q in the disk v . When this lever d is raised, the

pin *f* on the short arm *e* moves the bar *h* forward, the pin *j* traveling in the straight portion of the groove or way *k*. At the same time the end of the arm *n* is carried forward by the pin *o* and slot *p*, which gives the shaft *i* a quarter-turn on its axis, and thereby displays the danger-signal before the switch is in a position to be operated. When the lever *d* has been raised so as to clear the disk *v*, the disk *e* is given a half turn or revolution on its axis, which operates the switch-rails; but at the same time the pin *f*, becoming disengaged from the hook *g*, and the pin *j* engaging in the curved portion of the groove *k*, the bar *h* is held or locked in its forward position by the pin and groove, and the signal is thereby locked during the operation of the switch mechanism, and after the switch has been set. When the lever *d* and disk *c* have made a half-revolution, the lever *d*, which no longer engages with the bar *h*, is lowered to a vertical position, so as to be held or secured by the slot *q'* in the disk *v*.

During the return movement of the lever *d* to its original position, in order to again close the break in the main line, the danger-signal remains displayed until the switch has been completely operated, the pin *f* engages again with the hook *g*, and the lever is lowered or falls by its own weight to a vertical position, which movement operates the signal by drawing the bar *h* back to its original position, and the safety light or target is again displayed.

The advantages of my invention are that before the switch can be moved the danger-signal is set and retained or locked until the switch is brought back and mechanically locked in its original position.

Having thus described my invention, what I claim, and desire to secure by Letters Patent, is—

1. In a switch-stand, the combination of a rotating stem or shaft for operating the switch, an independently rotating or oscillating target or signal, a lever for operating the switch-stem, and devices for actuating the independently-rotating target from the switch-lever, whereby the movement of the lever causes the shifting of the signal before the switch is turned, substantially as and for the purpose specified. 45

2. In a switch-stand, the combination of a rotating stem or shaft for operating the switch, an independent rotating or oscillating target or signal, a lever for operating the switch-stem, devices for actuating the independently-rotating target from the switch-lever, whereby the movement of the lever causes the shifting of the signal before the switch is turned, and the locking mechanism, whereby the signal mechanism remains locked until the lever is returned to its original position, substantially as and for the purpose specified. 55

3. In a combined switch and signal-setting mechanism, the combination of a rotating stem 65 for actuating the switch, an independent rotating stem for actuating the signal, a lever for actuating the switch-stem, a slide-bar actuated by the switch-lever, and adapted to actuate the signal mechanism, and locking mechanism adapted to lock the slide during the rotation of the switch-stem, substantially as and for the purposes specified. 70

In testimony whereof I have hereunto set my hand this 8th day of October, A. D. 1883.

PRESSLEY COLEMAN.
